UNITED STATES PATENT OFFICE

2,224,194

HIGHWAY JOINT ALIGNMENT DEVICE

Robert E. Mitchell, Seattle, Wash.

Application February 28, 1936, Serial No. 66,276

12 Claims. (Cl. 94—51)

My present invention relates to the art of concrete road making equipment and more particularly to a highway joint alignment device.

This present application is an improvement over my United States Patent No. 2,031,901, issued Feb. 25, 1936, and illustrates and describes a device which is improved so as to more satisfactorily provide a true alignment for dowel pins, dowel pin tubes and expansion joint fillers.

This present device provides all the advantages of my former device and further provides a means which can be adjusted accurately to the curvature or crown of the road which is being constructed. Further means are provided to assure that each dowel securing member will grip and apply a uniform tension to the various dowel pins the device is securing in position.

Other and more specific objects will be apparent from the following description taken in connection with the accompanying drawings, wherein

Figure 1 illustrates my device as it appears in position when supporting the joint element in a crown highway as it is bowed prior to the pouring of the highway.

Figure 2 is a typical cross-sectional view through one of the supported dowels, taken through the extension bar of my device.

Figure 3 is an exploded perspective view showing the means for adjusting the dowel securing members.

Figure 4 is a fragmentary, sectional view of an alignment device similar to Figure 1 but enlarged and with certain parts being broken to better illustrate the adjusting means for the dowel securing members.

Figure 5 is a fragmentary top plan view of the operating means controlling the dowel securing hooks and for bowing the device.

Figure 6 is a cross-sectional view similar to Figure 2 illustrating the means employed for setting the expansion strip material to a predetermined depth.

Figure 7 is a cross-sectional similar to Figure 2 and 6, but showing my device as employed in the so-called semi-joint where the expansion strip material does not serve to provide a definite separation of the two abutting slabs, but merely provides a point of expected fracture.

Referring to the drawings, throughout which like reference characters indicate like parts, 10 designates the main supporting frame of my device. This, I prefer to make in the form of an angle having the upper flat plate 11 and the downwardly extending leg portion 12. I provide,

as reasonable security against tipping, tread members 14 on each end of frame 10. These should have considerable extent transversely of frame 10 so that as they rest upon the curb timbers 15 they will easily overcome any tendency of the device to tip or cant. Suitable handles as 17 are provided for more convenient handling of the device.

To gain maximum rigidity for the device and to provide against displacement of the joint material, I provide that leg 12 will extend well down into the pavement as it is bored and further provide that the same be notched as at 18 to provide clearance for the dowel pins 20. This construction is similar to my co-pending application referred to.

Secured to frame 10 is, preferably, a second angle bar 22. This bar serves a dual purpose. It assists in the alignment of the expansion strip material 23 and also provides a convenient support for the plurality of dowel bar securing hooks 24. Now, it has been found that unless some convenient adjusting means is provided it is difficult to have hooks 24 so positioned that they will securely engage each of the dowels 20 or dowel tubes 26 and seat them snugly against alignment bars 27. This is particularly true when the device is curved after the showing of Figure 1 or 4.

A convenient adjusting means is provided by eccentric bearing 28 which is mounted as will be best shown in Figures 2 and 6 on bolt 29 secured to bar 22. The bearing 28 has formed as a part of it a pointed indicator member 30 which assists in the movement of the eccentric bearing 28 and also indicates its setting. After its adjustment has been secured the nut on bolt 29 is tightened securely, pressing the face of the eccentric 28 against bar 22 where it is fixedly held against rotation.

All the various hook members 24 are preferably operated by single control bar 32, the connecting means being pins 31. Pins 31 should be a loose fit within holes 33 in hook members 24. Bar 32 should be of light material so that it may be sprung up or down to take care of the slight individual adjustment of hooks 24. Bar 32 is operated by the means shown in Figures 4 and 5 wherein a relatively short lever 35 is pivotally mounted at 36. One end of lever 35 is operatively connected to control bar 32 and to the opposite end is secured yoke 38. Yoke 38 is connected by means of the threaded, adjustable rod 40, to the operating lever 42. Lever 42 is pivotally supported to frame 10 by a raised lug carry-

ing the pivot pin 43. The end of lever 42 is formed at 45 so that a section of pipe may be set over the same for easy handling of the operating means. For convenient operation the portions generally shown in Figure 4 should be observed particularly in the heights of pivot pin 46 and pin 43, so that a toggle action will be provided wherein lever 42 is moved to the point where pin 47 goes down past the line joining points 43 and 46 so as to provide a toggle lock.

10 Inasmuch as bar 32 is disposed well below the certain upper surface 11 of frame 10, pressure exerted on bar 32 will bend frame 10 after the showing of Figures 1 and 4. The amount of this curvature is determined naturally by the pressure applied and this can be adjusted by means of the threaded rod 40 and its lock nut 50. It naturally follows that, by decreasing the distance between pivots 46 and 47 greater pressure will be exerted on bar 32 and consequently greater curvature provided in the entire device.

15 In setting the expansion joint material 23 in a joint it must be remembered that this material is usually of a fibrous material, usually impregnated with that tar like material, so that as the temperature increases, the same can be compressed as the abutting slabs of concrete expand. The material, however, has little resistance to wear and is of necessity placed somewhat below the wearing surface of the road. To accomplish this with certainty I provide a channel 52 which engages the top surface of expansion joint material 23 and is guided between members 12 and the downwardly extending leg 30 of angle 22. Its downward position is fixed adjustable by the flat headed bolts 53 which are screwed into plate 55 and secured in that adjustment by lock nut 56.

35 Where dummy or semi-joints are used it is customary to employ a shallow strip of suitable material usually of the same general character as the expansion strip and it is set substantially as shown, by dotted lines, in Figure 7 at 58. The same means are employed to assure its alignment and depth of seating, as is used for the expansion joint itself.

40 It is believed it will be apparent that where dowel tubes as 26 are used my hooks 24 can by adjustment of the eccentric bearings 28 be made 45 to hold tubes just as securely as the dowels themselves. This adjustment can be quickly effected in the field without the necessity of additional placement members. Varying widths of pavement can be accommodated, as in my former case, 50 by the extension frame 60 which is secured to frame 10 by a plurality of loops 61 and their co-acting key wedges 63.

55 The foregoing description and the accompanying drawings are believed to clearly disclose a preferred embodiment of my invention but it will be understood that this disclosure is merely illustrative and that such changes in the invention may be made as are fairly within the scope and spirit of the following claims.

60 I claim:

1. The combination with a supporting bar, of a series of centering members mounted on said bar adapted to receive dowel-pins, movable retaining means eccentrically mounted on the bar 65 for engagement with the dowel-pins to hold the latter in engagement with the centering members, a flat bar connecting said retaining means, a lever fulcrumed on said supporting bar and pivoted to said flat bar, means for moving said lever to simultaneously, alternately engage or 70 release said retaining means, and means for locking said retaining means in engaging position.

75 2. The combination with a main angle bar

release said retaining means, and means for locking said retaining means in engaging position.

2. The combination with a main angle bar having a lateral depending, notched flange, and means for supporting the ends of the bar, of a series of detachable, transversely arranged, spaced, centering arms and means for securing the arms to the bar, downwardly-extending, notched-flanges on the arms aligned with the notched flange, movable retaining means mounted on the bar for detachable engagement with dowel-pins to hold the latter in engagement with the notched-flanges of the arms, means for vertically adjusting said retaining means, and means for simultaneously releasing the retaining means.

10 3. The combination with a main supporting angle bar, of a series of centering members mounted on said bar adapted to receive dowel-pins, movable retaining means mounted on the bar for engagement with the dowel-pins to hold the latter in engagement with the centering members, means for vertically adjusting said retaining members, and means for simultaneously releasing said retaining means.

15 4. The combination with a main supporting angle bar, of an auxiliary angle bar rigid with said supporting bar, a series of centering members mounted on said auxiliary bar adapted to receive dowel-pins, movable retaining means mounted on the auxiliary bar for engagement with the dowel-pins to hold the latter in engagement with the centering members, means for vertically adjusting said retaining means, and means for simultaneously releasing said retaining means.

20 5. The combination with a main supporting bar, of a series of centering members mounted on said bar adapted to receive dowel-pins, movable retaining members mounted on the bar for engagement with the dowel-pins to hold the latter in engagement with the centering members, a flat bar connecting said retaining means, a lever fulcrumed on said supporting bar, means for moving said flat bar to simultaneously release said retaining means, and means for vertically adjusting said retaining means.

25 6. The combination with a main supporting bar, of a series of centering members mounted on said bar adapted to receive dowel-pins, movable retaining means mounted on the bar for engagement with the dowel-pins for holding the latter in engagement with the centering members, means for vertically adjusting said retaining means, a flat bar connecting said retaining means, a lever fulcrumed on said main bar and pivoted to said flat bar, means for moving said lever to simultaneously, alternately engage or release said retaining means, and means for locking said retaining means in engaging position.

30 7. The combination with a supporting bar, of a series of centering members mounted on said bar adapted to receive dowel-pins, movable retaining means mounted on the bar for engagement with the dowel-pins to hold the latter in engagement with the centering members, and means for vertically adjusting said retaining means, a flat bar connecting said retaining means, a lever fulcrumed on said supporting bar and pivoted to said flat bar, means for moving said lever to simultaneously, alternately engage or release said retaining means, and means for locking said retaining means in engaging position.

35 8. The combination with a main angle bar

having a lateral, depending, notched flange, and means for supporting the ends of the bar, of a series of detachable, transversely arranged, spaced, centering arms, and means for securing the arms to the bar, downwardly-extending, notched-flanges on the arms aligned with the notched flanges movable retaining means eccentrically mounted on the bar for detachable engagement with dowel-pins to hold the latter in engagement with the notched-flanges of the arms, and means for simultaneously releasing said retaining means.

9. The combination with a main supporting angle bar, of a series of centering members mounted on said bar adapted to receive dowel-pins, movable retaining means eccentrically mounted on the bar for engagement with the dowel-pins to hold the latter in engagement with the centering members, and means for simultaneously releasing said retaining means.

10. The combination with a main supporting angle bar, of an auxiliary angle bar rigid with said supporting bar, a series of centering members mounted on said auxiliary bar adapted to receive dowel-pins, movable retaining means eccentrically mounted on the auxiliary bar for engagement with the dowel-pins to hold the latter in engagement with the centering mem-

bers, and means for simultaneously releasing the retaining means.

11. The combination with a main supporting bar, of a series of centering members mounted on said bar adapted to receive dowel-pins, movable retaining means eccentrically mounted on the bar for engagement with the dowel-pins to hold the latter in engagement with the centering members, a flat bar connecting said retaining means, a lever fulcrumed on said supporting bar and pivoted to said flat bar, and means for moving said flat bar to simultaneously release said retaining means.

12. The combination with a main supporting bar, of a series of centering members mounted on said bar adapted to receive dowel-pins, movable retaining member means eccentrically mounted on the bar for engagement with the dowel-pins to hold the latter in engagement with the centering members, a flat bar connecting said retaining means, a lever fulcrumed on said main bar and pivoted to said flat bar, means for moving said lever to simultaneously alternately engage, or release said retaining means, and means for locking said retaining means in engaging position.

ROBERT E. MITCHELL.
